COMBINED CRUSHER, PULVERIZER, AND SCREEN

Oliver J. Moussette, Sr., Queens Village, N. Y.

Application September 3, 1935, Serial No. 39,059

3 Claims. (Cl. 83—9)

This invention relates to combined crushers, pulverizers and screens of that general class shown and described in United States Letters Patent No. 1,303,097 issued to me on the 6th day 5 of May, 1919, the present invention being an improvement thereon.

The object of the invention is to improve and increase the efficiency of the machine by providing novel means for feeding material in the path 10 of the crushing rollers or elements during the rotation of the drum, whereby said material will be directly and immediately acted upon by the crushing rollers and thorough pulverization of the material consequently expedited.

15 A further object of the invention is to provide a combined machine of the character described, having a material distributing element located at the intake end of the revolving drum and rotatable therewith for delivering material in front of the crushing rollers.

20 A further object is to form the material distributing element with a central opening having a spirally disposed scoop or cup on one side thereof which elevates the material entering the revolving drum and delivers the material through 25 said opening onto the crushing rollers.

25 A further object is to provide the distributing element with a circumferential attaching flange which fits between the breast piece and body of the drum and is locked against accidental displacement by engagement therewith.

30 Further objects and advantages will appear in the following specification, in which similar numerals of reference indicate corresponding parts in all the figures of the drawings.

35 Figure 1 is a vertical sectional view of the combined crusher, pulverizer and screen embodying the present invention.

Figure 2 is a transverse sectional view taken 40 on the line 2—2 of Figure 1.

Figure 3 is a face view of the material distributing element detached.

Figure 4 is a vertical sectional view taken on the line 4—4 of Figure 1.

45 Figure 5 is a rear view of the material distributing member detached, parts being broken away.

The improved machine forming the subject-matter of the present invention is principally designed for crushing, screening, and reclaiming 50 gold, silver, brass and other metals from materials while in a wet or moist condition and comprises spaced uprights 5 provided with bearings 6, said uprights being supported on a suitable foundation, indicated at 7. Mounted for rotation in the bearings 6 is a revolving drum 8 com-

prising a breast section 9, end section 10, and an intermediate section 11, the parts being provided with circumferential flanges 12 through which extend screws or similar fastening devices 13 whereby the sections are rigidly secured together. 5 The breast section 9 is substantially conical in shape and is provided with a cylindrical extension 14 which fits within the adjacent bearing 6 and is open at its outer or intake end 15 to permit the insertion of the adjacent end of a trough 16 by 10 means of which material is fed into the drum. The intermediate section 11 is provided with a lateral flange 17 to which is bolted or otherwise rigidly secured a wheel or pulley 18 around which extends a belt leading to a suitable source of 15 power for imparting rotary movement to the drum. The rear section 10 of the drum is formed with a cylindrical extension 19 which fits within the other bearing 6 and on the end of this extension 19 is a cylindrical screen 20, the outer end 20 of which is open, as best shown in Figure 1 of the drawings. Disposed within the intermediate section of the drum 11 are lining plates 21 preferably formed of hard steel, and loosely mounted within the drum and bearing against the lining plates 21 are conical crushing elements or rollers 22 preferably pivotally connected at 23 to permit them to conform to the inclination of the lining plates. The intermediate drum section 11 is provided with the usual clean out opening and 25 closure plug, indicated at 23'.

30 Disposed within the breast section 9 of the drum and extending transversely across the intake opening 15 is a material distributing member 24. The distributing member 24 comprises a vertical 35 plate or disc 25 having a central opening 26 formed therein substantially in alinement with the intake opening 15 and disposed on one side of the plate at the central opening 26 thereof is a spirally disposed scoop or cup 27 which serves to elevate the material delivered by the trough 16 and discharge said material through the opening 26 at the front of and in the path of movement of the crushing rollers or elements 22. The outer portion of the scoop 27 is closed by a segmental 40 plate 28 so as to confine the material within the scoop and cause said material to be carried upwardly for delivery to the crushing rollers when the drum is rotated. The peripheral edge of the plate 25 is extended laterally to form a circumferential attaching flange 29 and this flange 29 fits within a groove or seating recess 30 formed by offsetting the metal constituting the breast section 9, as best shown in Figure 1 of the drawings. It will thus be seen that the outer periph- 45 50 55

eral edge of the plate 24 bears against the shoulder 31 formed by offsetting the breast section 9, while the attaching flange 29 fits within the recess 30 thus forming, in effect, a stepped joint between the parts. The lining plate 21 forms a closure for one side of the seating recess 30 and said lining plate bears against the flange 29 and serves to prevent inward movement of the distributing member, as best shown in Figure 1 of the drawings. It will thus be seen that by positioning the distributing member between the breast section 9 and intermediate section 11 of the drum and tightening the adjacent bolts or screws 32, the distributing member will be securely held against accidental displacement. It will here be noted that the breast section 9 forms, in effect, a closure for the open side of the cup or scoop 27 so that the material will be confined within the scoop by the adjacent wall of the breast section.

In operation, the drum is rotated and the material from the trough is fed into the intake end of the drum and will be directed downwardly by the conical walls of the breast section 9 into the cup or scoop 27. As the distributing member is secured to and rotates with the drum, the material entering the breast section will be taken up by the scoop and delivered through the central opening 26 of the distributing member at the front of the crushing rollers so that said material will be directly and immediately acted upon by said crushing rollers and pulverization of the material consequently materially expedited. As the material is crushed or pulverized it passes through the cylindrical extension 19 into the screen 20, the fine material being discharged through the mesh of the screen onto a concentrating table and the coarser material being discharged at the open end of the screen, as fully set forth and described in my prior patent previously mentioned. It will thus be seen that, owing to the construction and location of the distributing member, the material is fed directly in front of the crushing rollers thus expediting the pulverization of the material and obtaining better and quicker results than heretofore.

It will further be noted that due to the spiral motion of the distributing member, said member has a tendency to drain the material, by displacement, away from the feed end of the crusher. In other words, the distributing member acts as a force feed and thereby enables the operator to feed the machine much faster than would be possible without said distributing member.

From the foregoing description, it is thought that the construction and operation of the machine will be readily understood by those skilled in the art and further description thereof is deemed unnecessary.

Having thus described the invention, what is claimed as new is:

1. A machine of the class described comprising a rotary drum including a substantially conical breast section having an intake end, a rear section having a discharge end, and an intermediate section, means for securing said sections in assembled position, said breast section being provided in its inner face with a continuous seating recess, crushing rollers disposed within the intermediate drum section, and a distributing member disposed within the breast section of the drum and comprising a disc having a continuous circumferential flange fitting within the recess and secured against displacement by engagement with the intermediate section, said disc being provided with a central opening and formed on one side thereof with a spirally disposed scoop for delivering material through the opening in the disc into the path of movement of the crushing rollers, the wall of the breast section coating with the scoop to hold the material therein during rotation of the drum. 5 10 15

2. A machine of the class described comprising a rotary drum including a breast section having an intake end and provided with a circumferential seating recess, a rear section having a discharge end, and an intermediate section, a lining fitting within the intermediate section, crushing rolls mounted for rotation within said intermediate section and bearing against the lining, and a material distributing member extending transversely of the breast section of the drum and provided with a laterally extending flange fitting within said recess and bearing against the adjacent lining, said distributing member being formed with a central opening and being provided with a spirally disposed scoop for delivering material through said opening in the path of rotation of the crushing rolls. 30 35

3. A machine of the class described comprising a rotary drum including a breast section 40 provided with an intake end and having its walls offset to form a stop shoulder defining a circumferential seating recess, a rear section having a discharge end, an intermediate section interposed between the breast and end sections and secured 45 thereto, liner plates disposed within the intermediate section, crushing rolls mounted for rotation on the liner plates, and a distributing member extending transversely of the breast section of the drum and bearing against said stop shoulder, said distributing member being provided with a laterally extended flange fitted within the seating recess and contacting with the adjacent liner plate, said distributing member being formed with an intake opening and provided with a scoop for delivering material through said opening into the path of rotation of the crushing rolls. 50 55
